(57) **CLAIM**

The ornamental design for a storage cabinet, as shown and described.

DESCRIPTION

FIG. 1 is a front perspective view of a storage cabinet showing my new design;

FIG. 2 is a rear perspective view thereof;

FIG. 3 is a front perspective view of a second embodiment of the storage cabinet shown in FIG. 1;

FIG. 4 is a rear perspective view thereof;

FIG. 5 is a front perspective view of a third embodiment of the storage cabinet shown in FIG. 1; and,

FIG. 6 is a rear perspective view thereof.

The surface(s) or portion(s) of the article not shown in the drawing or described in the specification form(s) no part of the claimed design.
